UNITED STATES PATENT OFFICE

108,402

DESIGN FOR A COMBINED LAMP BASE AND RADIO

Noel E. Pool and Fred N. Curby, Salt Lake City,
Utah

Application December 28, 1937, Serial No. 66,782

Term of patent 7 years

To all whom it may concern:

Be it known that Noel E. Pool and Fred N. Curby, citizens of the United States, residing at Salt Lake City, in the county of Salt Lake and the State of Utah, have invented a new, original, and ornamental Design for a Combined Lamp Base and Radio, of which the following is a specification, reference being had to the accompanying drawing forming a part thereof.

Figure 1 is a side elevation of the combined lamp base and radio, and

Figure 2 is a top plan view of the same showing the new design.

We claim:

The ornamental design for a combined lamp base and radio, as shown.

NOEL E. POOL.
FRED N. CURBY.
